UNITED STATES PATENT OFFICE

JACOB STUART SCHAFER, OF NEW YORK, N. Y.

LAMP AND HEATER.

Application filed October 25, 1923. Serial No. 670,710.

To all whom it may concern:

Be it known that JACOB STUART SCHAFER, a citizen of the United States, residing at New York, in the county of New York and 5 State of New York, has invented certain new and useful Improvements in Lamps and Heaters, of which the following is a specification.

This invention relates to an improvement 10 in electrical apparatus, and the same has for its object to provide an apparatus which may be used for illuminating purposes or for heating or cooking. The apparatus may also be used simultaneously both for 15 illuminating and heating or cooking.

My invention consists of a novel construction of a combined electric heater and electric table lamp, wherein I utilize the hollow base of the lamp structure as an electric 20 heater, so that when the lamp is inverted the heater can be operated to heat the room or if desired to heat an article as water, etc.

A further object of this invention is to construct a table lamp with a hollow base, 25 the latter being utilized as a heating compartment and adapted to operate simultaneously with the lamp.

A further object of this invention is to construct a combined electric table lamp 30 and electric heater, the latter disposed within the base of the lamp. A lamp shade normally resting on supports and adapted to be utilized as a cover for articles to be heated when the lamp is inverted and the 35 heater is in use.

A further object of this invention is to provide a combined lamp and heater with abutments for a shade and when the lamp is in an inverted position the abutments act 40 as supports for the lamp and heater.

A further object of this invention is to construct a combined electric lamp and electric heat reflector.

In the drawings; Figure 1 is a front view 45 partly in section, made in accordance with my invention.

Figure 2, is a bottom view of my device.

Figure 3, is a front view of the device in an inverted position.

Figure 4, is a front view partly in section of the device used as a heat reflector.

Figure 5, is a diagrammatic view of the wiring.

Referring to the drawing, the numeral 1, 55 denotes a standard for a lamp having its lower portion formed into a hollow base 2.

To the upper part of the standard there is shrunk or otherwise permanently attached a sleeve 3, to which there are integrally fixed abutments or supports 4, these abutments are made of flexible metal and the ends 5, are turned upon themselves so as to form smooth resting means. Upon the abutments a shade 6, is placed, the abutments preferably being flexed so as to hold 60 the shade in a snug manner. At the upper end of the standard an electric bulb 7 is screwed or otherwise attached.

Within the hollow base 2, I place my heater 10, which is a bare wire supported 70 and properly insulated by the asbestos or other non-conducting material 11, the latter is in turn fixed to the base 2, by means of lugs 12, and screws or bolts 13. To the bottom of the base I have placed a heat 75 insulating ring 14, and within this ring I place a grid 8, or any meshed wire or any metal of highly heat resisting quality. The grid and asbestos ring are both attached to the bottom of the base by means of long 80 screws 15. Underneath the base I place an asbestos ring 16, to prevent any heat reaching a table or other support.

Wires 17, 17', lead the current to a switch 18, which throws the current either to the 85 lamp or heater or if desired to both simultaneously. Figure 5, clearly shows the wiring arrangement. In entering through the wire 17, the switch 18, and the segment 22, the current enters and lights the bulb 7, 90 and leaves by the wire 17', thus completing its circuit and only the bulb is affected. Should the switch be turned so that it covers the segment 23, then only the heater 95 is affected, however, if the switch is so placed that it covers portions of segments 22, and 23, then the current divides in parallel and both bulb and heater are affected.

In Figure 3, I have shown the device in an inverted position and with current 100 turned on the heater is in use. If desired the shade may be placed over the heated object, and thus make the heat more intense and thereby cause an oven effect.

In Fig. 4, I have illustrated a modification of my device which embodies a heat reflector. The reflector consists preferably of a highly polished metal shell 31, which is parabolic or dome-shaped and serves to reflect the heat waves received from the 110 heater and direct them outwardly from the inner concave surface. The heater unit

comprises a suitable heating element such as a bare high resistance wire 32, coiled helically upon a refractory cylinder 34, of fire clay, asbestos or other suitable material. The wiring around the refractory cylinder is done in any approved manner.

The refractory cylinder and reflector are fastened to a lug 35, within the standard 1. The wide end 36, of the reflector is held 10 in position within the base by any desired means such as a flange 38, which is fastened to the base 2.

A grid 37, has the dual function of acting both as a support for articles to be heated 15 and as a guard invariably used in heat reflectors. This grid is also placed and held in position by the flange 38.

In order that the column or shaft of reflected heat waves may be directed at varying angles as desired, I may provide a swivel connection between the parabolic reflector and the support or stand.

Thus by the above described construction are accomplished among others, the objects 25 hereinbefore referred to.

As many changes could be made in the above construction and many apparently widely different embodiments of this invention could be made without departing from the scope thereof, it is intended that all matter contained in the above description or 30 shown in the accompanying drawing shall be interpreted as illustrative and not in a limiting sense.

It is also to be understood that the language used in the following claims is intended to cover all of the generic and specific 35 features of the invention herein described.

Having described my invention what I claim as new and desire to secure by Letters Patent is:

1. In combination, a connecting member, an electrical connecting means at one end thereof for a lamp, electrical connecting means at the other end for a heater, and means for holding the lamp end uppermost, and means for holding the heater end uppermost.

2. A combined electric lamp and heater, means for connecting them in superimposed relation, a shade for the lamp, means for supporting the shade when the lamp is in an upright position, said means also adapted to support the lamp and heater in an inverted position and so arranged that both lamp and heater could be used simultaneously.

3. A device of the class described, comprising, a standard having a hollow base,

lamp lighting means affixed to the upper part of the standard, a parabolic heater placed and conforming to the contour of the base, and electrical connections to said means and heater, a mechanism attached to the standard and adapted to support the device in an inverted position and so arranged that both lamp lighting means and heater could be used simultaneously.

4. A device of the class described, comprising, a standard having a hollow base, 70 lamp lighting means affixed to the upper part of the standard, a parabolic heater placed within and conforming to the contour of the base, electrical connections to said means and heater, a grid spanning the open space of the heater, a mechanism attached to the standard and adapted to support the device in an inverted position and so arranged that both lamp lighting means and heater 75 could be used simultaneously.

5. A combined electric lamp and heater, means for connecting them in superimposed relation, a shade for the lamp, said shade is so constructed as to be adapted to be used as a cover for articles to be heated.

6. A device of the class described, comprising, a standard having a hollow base, terminals for receiving a lamp at the upper part of the standard, a heat reflector placed within the hollow base, terminals for receiving a heater within the base, and electrical connections to said terminals.

7. A device of the class described, comprising, a standard having a hollow base, a lamp affixed to the upper part of the standard, a shade for the lamp, supports for the shade affixed to the standard, a heat reflector arranged within the base, said supports protruding above the lamp so as to enable them to carry both lamp and heat reflector when in an inverted position.

8. A device of the class described, comprising, a standard having a base, terminals for receiving a lamp at the upper part of the standard, terminals for receiving a heater arranged at the base, and electrical connections to said terminals, and means to support the device in an inverted position and so arranged that both lamp and heater when in place, could be used simultaneously.

9. The combination of a lamp and a heater, electrically interconnected and arranged at opposite ends of a standard, means for supporting the standard in a normal position, and means for supporting the standard in an inverted position.

In testimony whereof I affix my signature.
JACOB STUART SCHAFER.
